Primary Examiner — Garth Rademaker*(74) Attorney, Agent, or Firm* — Vincent K. Gustafson; Jenkins, Wilson, Taylor & Hunt, P.A.(57) **CLAIM**

The ornamental design for a gutter for a grease containment apparatus, as shown and described.

DESCRIPTION

FIG. 1 is a perspective view of a gutter for a grease containment apparatus according to my new design;

FIG. 2 is a front elevation view of the gutter for a grease containment apparatus;

FIG. 3 is a rear elevation view of the gutter for a grease containment apparatus;

FIG. 4 is a right side elevation view of the gutter for a grease containment apparatus;

FIG. 5 is a top plan view of the gutter for a grease containment apparatus; and,

FIG. 6 is a bottom plan view of the gutter for a grease containment apparatus.

The left side elevation view of the gutter for a grease containment apparatus is a mirror image of the right side elevation view thereof.
